CHOKE VALVE ACTUATOR

Ernest James Hifner, Lexington, Ky., assignor to
Nancy T. Hifner, Lexington, Ky.

Application November 1, 1934, Serial No. 751,216

9 Claims. (Cl. 123—119)

My invention relates to an automatic choke actuator.

An important object of the invention is to provide a device of the above mentioned character which will quickly close the choke valve when the engine is cranked and open the choke valve, partly or wholly, when the engine starts operating upon its own power and will also retain the choke valve open when the engine warms up to or above 10 the normal working temperature.

A further object of the invention is to provide a device of the above mentioned character, which is adjustable to accommodate itself to the working conditions of the engine.

15 A further object of the invention is to provide a device of the above mentioned character which is wholly automatic in operation and reliable in such operation.

Further objects and advantages of the invention will be apparent during the course of the following description.

20 In the accompanying drawings forming a part of this application and in which like numerals are employed to designate like parts throughout 25 the same,

Figure 1 is a side elevation of a device embodying my invention, showing the same in use,

Figure 2 is a central vertical longitudinal section through the suction operated unit of the 30 device,

Figure 3 is a transverse section taken on line 3—3 of Figure 2.

Figure 4 is a perspective view of a valve element included in the device,

35 Figure 5 is a central vertical longitudinal section through a thermostatic valve device included in the invention,

Figure 6 is a transverse section taken on line 6—6 of Figure 5,

40 Figure 7 is a horizontal section taken on line 7—7 of Figure 5.

Figure 8 is a central vertical longitudinal section through the suction operated unit of the device, showing the outer sliding tube in the 45 lowered or contracted position, and,

Figure 9 is a perspective view of the elements of a housing.

In the drawings, wherein for the purpose of 50 illustration is shown a preferred embodiment of my invention, the numeral 10 designates the cylinders of an internal combustion engine having an intake manifold 11. The numeral 12 is the carburetor having an air intake pipe 13. The carburetor has the usual throttle valve 14 controlling its outlet and this throttle valve is actu-

ated by a crank 15 connected with the accelerator, as is customary. Arranged within the air intake pipe 13 is a pivoted choke valve 16, which is held in the open position when the engine is not running and also when it is heated up to or above 5 a normal working temperature. The swinging movement of this choke valve is controlled entirely by the actuator unit, to be described.

This actuator unit embodies a suction casing or chamber 17, preferably horizontally arranged. 10 This casing has feet or brackets 18 so that it may be bolted in position. The casing may be located at any suitable position upon the engine or chassis. The suction casing 17 is provided near one end and upon its top with a valve casing 19, the 15 upper end of which is closed by a removable cap or plug 20. A suction pipe 21 is connected with the cap 20 and communicates with the interior of the valve casing 19. The cap 20 is provided with a depending annular valve seat 22, to be engaged by an upwardly seating disk-valve 23, adapted to rest upon a flange 24, when in the unseated position. This disk-valve is provided with a central opening 25 and two outer openings 26. 20 A weight-tube 27 is carried by the disk-valve 23 and its bore communicates with the opening 25 and has the same diameter. The diameters of the openings 25 and 26 are identical, and the combined cross-sectional areas of these three openings 25 and 26 is equal to the cross section area 30 of the bore of the suction pipe 21. When the disk-valve 23 is in the unseated position resting upon the flange 24 the three openings 25 and 26 are uncovered and hence the entire degree of suction within the pipe 21 is transmitted to the 35 casing 17. When the disk-valve 23 is raised and engages the seat 22, openings 26 are cut out of communication with the bore of the pipe 21, and hence the transmission of suction 40 from the pipe 21 to the casing 17 is reduced. It might be stated at this point that when the engine is cranked and not operating upon its fuel, a suction is created in the pipe 21 but not sufficient to seat the disk-valve 23, whereby this entire suction is transmitted to the casing 17. When 45 the engine starts to operate upon its fuel, the suction in the pipe 21 is rapidly increased to such an extent that the disk valve 23 is seated, cutting off communication between the openings 26 and the pipe 21, whereby this suction is transmitted to the casing 17 only through the central opening 25, thus reducing the degree of suction 50 within the casing 17. The degree of suction within the casing 17 may also be regulated by a 55

needle valve 27, which partly or wholly covers a bleeding port 28.

A suction operated element is provided, comprising an upstanding tube 29, rigidly attached to the casing 17. Mounted to slide upon this tube is an outer tube 30, having an air-tight fit therewith. The upper end of this tube is closed by a head 31. This head projects laterally beyond the tube 30 and is preferably formed square. A support or guard 32 is rigidly attached to the casing 17 and is vertically arranged and surrounds the telescoping tubes 29 and 30. This support or guard is square in horizontal cross-section and the head 31 slidably contacts therewith and is thereby held against turning movement. A stationary spacer 33 is rigidly attached to this support or guard and has an opening for the free passage of the outer tube 30. A compressible coil spring 34 is arranged between the spacer 33 and the head 31 and serves to elevate the outer tube 30, while a retractile coil spring 35 is arranged beneath the spacer and is attached thereto and also attached to the lower end of the tube 30 and serves to raise the outer tube 30. By the arrangement of its springs and the spacer, the operation of these springs in opposing the downward movement of the tube 30 remains uniform throughout the entire downward movement of the tube 30, that is, these springs do not exert an increased force opposing the downward movement of the tube 30 as the tube approaches its lowermost position.

Arranged above the head 31 is a vertical rod 36, rigidly attached thereto and this rod carries a transverse pin 37 operating within an elongated slot 38 formed in one arm 39 of a bell crank lever, which is pivoted at 40. The other arm 41 of this bell crank lever is connected by means of a rod or wire 42 with the crank 17 of the choke valve 16.

The suction pipe 21 is connected with a two-way valve casing 43, which is rigidly mounted upon a stationary support 44, rigidly held in place upon the engine or chassis. This valve casing has a valve seat 45, for coaction with an upwardly seating valve element 46, having a stem 47 extending through a stuffing box 48 for forming an air-tight joint therewith. The stem is urged downwardly by a compressible coil spring 49, which normally holds the valve element 46 in the lower unseated position. The outlet end of the valve casing 43 is connected with a pipe 50, which leads into the intake manifold, as shown.

Arranged beneath the support 44 is a vertically adjustable slide 51, operating within guides 52, and raised and lowered by an adjusting screw 53, having screw-threaded engagement with a lug 54, rigidly attached to the slide 51. The adjusting screw 53 has a swivelled connection with a stationary arm 55, arranged above the support 44. A generally U-shaped thermostatic element 56 has one arm rigidly attached to the slide 51, at 57, while its upper free arm is arranged beneath and disposed to engage the lower end of the stem 47. This thermostatic element may be of the usual type formed of two metals having different coefficients of expansion, whereby the upper arm of the thermostatic element rises and elevates the valve element 45, when the thermostatic element is heated.

The operation of the device is as follows:

When the engine is cold and is not running, the throttle lever is suitably adjusted to supply the gas and the choke valve 16 is standing open. The operator then steps on the starter and the engine is cranked and this immediately creates

suction within the pipe 21 above the disk-valve 23, as the valve element 46 is now completely opened, the thermostatic element 56 being cold. This suction within the pipe 21 is transmitted to the suction casing 17 through the three holes 25 and 26 as this suction is not sufficient to seat the valve-disk 23. However, the suction transmitted to the casing 17 is sufficient to quickly move the outer tube 30 downwardly, and this movement quickly closes the choke valve 16, whereby a rich mixture is drawn into the cylinders of the engine. When the engine starts operating upon its own power or upon the explosive charge, the increased suction within the pipe 21 seats the disk-valve 23, and the suction must then be transmitted to the casing 17 entirely through the single reduced opening 25, and this reduces the suction within the suction casing 17, so that the springs 34 and 35 now overcome this suction action and shift the tube 30 upwardly, again opening the choke valve, in whole or part. The needle valve 27 has been adjusted to control the bleeding action of the port 28, and this bleeding action is regulated with respect to the degree of suction passing through the single port 25, so that the suction is lowered sufficiently within the casing 17 to permit the springs to shift the tube 30 upwardly, as explained. As the engine continues to operate upon the explosive charge, the disk-valve 23 remains seated, whereby the suction remains reduced in the casing 17, and the choke valve remains open. During this operation of the engine upon the explosive charge, the thermostatic element 56 is heated and operates to gradually seat the valve element 46. This further reduces the suction within the casing 17 and finally when the valve element 46 is seated, suction is entirely cut off from the casing 17 and the remaining suction therein is dissipated through the bleeding port 28. Hence when the engine is operating on its own power at or above normal temperature the valve element 46 is seated and the choke valve remains entirely open. When the engine is operating on its own power, at or below normal temperature, the disk 23 is in the upper position and the vacuum is transmitted below the disk only through the central hole 25. The valve element 46 begins to close, due to the action of the thermostatic action of the element 56. The uncovered area of the bore of the valve seat 45 has to be equal to the area of the opening 25, before the disk-valve 23 drops. Accordingly, when the thermostatic element 56 moves the valve element 46 toward the seat 45, the area of the uncovered bore of the valve seat must equal the area of the opening 25, and when this occurs, the disk valve will drop. When this occurs, the valve element 46 is very close to its seat, and may be only about .005 of an inch from contact with the seat 45, and the tension of the springs 34 and 35 is so great that it cannot be overcome by any reduced suction which could pass the valve element 46 when it is brought sufficiently close to its seat 45, to cause the disk valve 23 to drop, and hence there is no downward movement of the outer tube 30.

It is to be understood that the form of my invention herewith shown and described is to be taken as a preferred example of the same and that various changes in shape, size and arrangement of parts may be resorted to without departing from the spirit of the invention or the scope of the subjoined claims.

Having thus described my invention, what I claim is:

1. The combination with the intake manifold 75

5 of an internal combustion engine and a carburetor having a normally open choke valve, of a suction operated device having communication with the intake manifold to receive suction therefrom and connected with the normally open choke valve to close the same when the engine is cranked, and automatic means to reduce the suction within the suction operated device upon the increase of suction within the intake manifold due to the operation of the engine upon its fuel.

10 2. The combination with the intake manifold of an internal combustion engine and a carburetor having a normally open choke valve, of a suction operated device having communication with the intake manifold to receive suction therefrom and connected with the normally open choke valve to close the same when the engine is cranked, and means actuated upon the increase of suction within the intake manifold to reduce the means of communication between such manifold and suction operated device so that the suction within such device is lowered and the choke valve moved toward the open position when the engine operates upon its fuel.

15 3. The combination with the intake manifold of an internal combustion engine and carburetor having a normally open choke valve, of a suction operated device connected with the choke valve to close it, yielding means operating in opposition to the suction operated device to open the choke valve, a conduit connecting the suction operated device and the intake manifold, and an automatic valve connected in the conduit, said valve including a valve element adapted when seated to afford a reduced passage and when unseated to produce a passage which is greater than the reduced passage; said valve element being adapted to remain unseated when the engine is being cranked and to be automatically seated by the increased suction when the engine is operating upon its fuel.

20 4. The combination with the intake manifold of an internal combustion engine and carburetor having a normally open choke valve, of a suction operated device connected with the choke valve to close it, yielding means operating in opposition to the suction operated device to open the choke valve, a conduit connecting the suction operated device and the intake manifold, an automatic valve connected in the conduit and remaining unseated when the engine is cranked and being automatically seated by the increased suction when the engine is operated upon its fuel, said valve affording a reduced passage when seated and a passage greater than the reduced passage when unseated, and means for affording a restricted communication between the interior of a suction operated device and the atmosphere for regulating the degree of suction therein.

25 5. The combination with the intake manifold of an internal combustion engine and carburetor having a normally open choke valve, of a suction operated device connected with the choke valve to close it, yielding means operating in opposition to the suction operated device to open the choke valve, a conduit connecting the suction operated device and the intake manifold, a valve connected in the conduit and remaining unseated when the engine is cranked and being seated when the engine is operated upon its fuel, said valve affording a reduced passage when seated and a passage greater than the reduced passage when unseated,

means for affording a restricted communication between the interior of the suction operated device and the atmosphere, and a thermostatic device including a valve connected in the conduit and adapted to completely close the conduit.

30 6. The combination with the choke valve of the carburetor of an internal combustion engine, of a suction operated device connected with the choke valve to move it to the closed position, yielding means to move the choke valve to the open position, a conduit for connecting the suction operated device with the intake manifold of the engine, and an automatic valve connected in the conduit and including a valve element adapted to afford a reduced passage when seated and a larger passage when unseated, said valve element being so weighted that it remains unseated when the engine is cranked and is automatically seated by the increased suction when the engine operates upon its fuel.

35 7. The combination with the intake manifold of an internal combustion engine and a carburetor having a normally open choke valve, of a suction operated device having communication with the intake manifold to receive suction therefrom and connected with the normally open choke valve to close the same when the engine is cranked, automatic means to reduce the suction within the suction operated device upon the increase of suction within the intake manifold due to the operation of the engine upon its fuel, a valve device for controlling the communication between the suction operated device and the intake manifold, and a thermostatic element to actuate the valve device and arranged suitably near the engine to be acted upon by the heat therefrom.

40 8. The combination with the intake manifold of an internal combustion engine and a carburetor having a normally open choke valve, of a suction operated device having communication with the intake manifold to receive suction therefrom and connected with the normally open choke valve to close the same when the engine is cranked, automatic means to reduce the suction within the suction operated device upon the increase of suction within the intake manifold due to the operation of the engine upon its fuel, a valve device for controlling the communication between the suction operated device and the intake manifold, a thermostatic element to actuate the valve device and arranged suitably near the engine to be acted upon by the heat therefrom, and adjustable means to regulate the action of the thermostatic element.

45 9. The combination with the intake manifold of an internal combustion engine and a carburetor having a normally open choke valve, of a suction operated device having communication with the intake manifold to receive suction therefrom and connected with the normally open choke valve to close the same when the engine is cranked, automatic means to reduce the suction within the suction operated device upon the increase of suction within the intake manifold due to the operation of the engine upon its fuel, and means to move the choke valve to the open position upon the reduction of suction within the suction operated device.
